(57) **CLAIM**

We claim the ornamental design for double-wide building structure for a carwash, as shown and described.

DESCRIPTION

FIG. 1 is a front elevational view of a double-wide building structure for a carwash showing our new design;
FIG. 2 is a right side elevational view thereof;
FIG. 3 is a rear elevational view thereof;
FIG. 4 is a left side elevational view thereof; and,
FIG. 5 is a top plan view thereof.
